UNITED STATES PATENT OFFICE

2,492,287

GARMENT HANGER

Edward F. Hogan, Andover, Mass., assignor to
The Boita Company, Lawrence, Mass., a corpora-
tion of Massachusetts

Application March 1, 1946, Serial No. 651,132

1 Claim. (Cl. 223—93)

1

This invention relates to improvements in garment hangers and the principal object of the invention is to provide a garment hanger construction for separately supporting independently or selectively one or several garments thereby providing a hanger of greater capacity than heretofore produced and one which is adapted to support a greater variety of garments such, for example, as a coat, a slip having shoulder straps, sleeveless garments, trousers, etc.

A further object of the invention is to provide an integral garment hanger of the character above described which can be conveniently moulded at a minimum cost of production.

Another object of the invention is to provide a garment hanger of the character described, adapted to fit any style of garment, with no adjustable parts and which requires no assemblage.

A further object of the invention is to provide a garment hanger of the character described in which all of the garment-engaging members are provided with rounded edges adapted to avoid snagging or ripping of the garment.

These and other objects and features of the invention will more fully appear from the following description and the accompanying drawings and will be particularly pointed out in the claim.

Preferred embodiments of the invention are shown in the accompanying drawings, in which,

Fig. 1 is a side view of one form of the garment hanger embodying the invention;

Fig. 2 is a vertical sectional view on line 2—2

Fig. 1;

Fig. 3 is a detail view of one of the arm portions of a modified form of hanger;

Fig. 4 is a sectional view on line 4—4 Fig. 3;

Fig. 5 is a detail view of one of the arm portions of another modified form of hanger; and,

Fig. 6 is a vertical sectional view on line 6—6 Fig. 5.

The features of the garment hanger illustrated in the drawings which are common to all comprise a body of resilient thermoplastic material having a central neck portion 1 with a hook-shaped suspension member 2 extending upwardly from the central portion thereof and outwardly and downwardly converging arms 3 and 4 extending in opposite directions from the neck portion. The neck and arms comprise a continuous thin web 5 bounded by upper and lower relatively thick rounded ribs 6 and 7, the ribs at the ends of the arms presenting rounded shoulders 8. The upper portion of each arm is provided approximately midway of its length with a downwardly extending slot 9 which is bounded by an extension 10 of

2

the rib 6. Each of the arms is provided with an inwardly extending horizontal branch 11 preferably having a central web 12 forming a continuation of the web 5 and each of the horizontal branches is provided with means for preventing a garment hanging thereon from slipping off the end thereof. In the constructions shown the branches 11 are provided with a series of teeth 13 and with an upwardly extending terminal hooked portion 14.

In the construction shown in Fig. 1 a webbed finger 15, which is bounded by the lower rib 1, extends inwardly beneath and in parallelism to the branch 11. This is spaced at its outer end 15 from the branch 11 and converges upwardly toward and in close proximity to the lower rib of the branch and by reason of the resilience of the material provides a clamp for holding a garment in the slot thereby provided.

The lower rib 1 of each of the arms has beneath the neck portion an upwardly curved extension 16 forming a hook adapted also to engage another garment.

The hanger thus constructed comprises a main body having an upwardly extending neck portion and downwardly extending curved arms adapted to fit the shoulder and neck portion of a coat. The slots 9 in the upper ribs provide means for holding the straps of a slip or the like, the extension 16 forming the upper wall of the slot being curved to form a substantial continuation of the upper rib of the hanger.

The inwardly extending hooked-shaped horizontal branch provides a support for another garment while the clamping finger, which lies beneath the horizontal branch, affords means for clamping another garment. The hooks which extend inwardly from the lower rib beneath the neck portion form supports which can be used either singly or in combination to hang another article of clothing or any suitable relatively small garment or device.

The construction illustrated in Figs. 3 and 4 differs from that above described in that the resilient means for clamping a portion of a garment against the under rib of the horizontal branch 11 is in the form of a finger 17 having a downwardly curved rounded end portion 18, the base of the finger 17 being a relatively thick portion 19 of the lower rib 1.

The construction illustrated in Figs. 5 and 6 is similar to that illustrated in Figs. 3 and 4 in that the resilient finger 17, which extends from the thickened terminal portion 20 of the arm of the hanger, is consequently longer and provides

a greater garment-receiving area. Each of the constructions above described is adapted to independently support a larger number of garments than hangers heretofore constructed without danger of snagging or tearing them and is consequently of greater utility than those heretofore made. So far as I am aware no garment hanger has heretofore been constructed in which the utility of resilient thermoplastic material has been utilized clampingly to support a garment or portions thereof.

It will be understood that the particular embodiments of the invention shown and described herein are of an illustrative character and not restrictive of the meaning and scope of the following claim.

Having thus described the invention, what is claimed as new, and desired to be secured by Letters Patent, is:

An integral garment hanger of molded resilient thermoplastic material having a central neck portion, a hook-shaped suspending member extending upwardly therefrom, outwardly and downwardly curved arms extending in opposite directions from said central neck portion in the vertical plane thereof, said neck portion and arms having a thin web bounded by relatively thick rounded upper and lower ribs, each of said

arms having in proximity to the respective ends thereof a horizontal branch extending inwardly therefrom having a thin web surrounded by continuous portions of the lower rib with the upper portion of the rib thereof having upwardly extending projections and an upwardly extending hooked end of greater length than said projections, and a supplemental upwardly curved arm having rounded surfaces extending inwardly from the end portion of each arm in the same plane therewith and resiliently engaging the lower rib of the respective branch thereby providing a yielding clamp for engagement of a portion of a garment between the supplemental arm and the inwardly extending branch of the hanger.

EDWARD F. HOGAN.
